UNITED STATES PATENT OFFICE

100,401

DESIGN FOR AN ASHTRAY

Walter H. Vogel, San Luis Obispo, Calif.

Application November 27, 1935, Serial No. 59,804

Term of patent 14 years

To all whom it may concern:

Be it known that I, Walter H. Vogel, a citizen of the United States of America, residing at San Luis Obispo, county of San Luis Obispo, and State of California, have invented a new, original, and ornamental Design for an Ashtray, of which the following is a specification, reference being had to the accompanying drawing forming a part thereof.

I claim:

The ornamental design for an ashtray as shown.

WALTER H. VOGEL.
